METALLIC SHINGLE

Charles J. Rateike, Chicago, Ill., assignor, by direct and mesne assignments, of fifty-five percent to Nils G. Olsson, Aurora, Ill.

Application April 16, 1932, Serial No. 605,655

9 Claims. (Cl. 108—17)

This invention relates to metallic shingles and more particularly to an improvement in the inter-connecting features thereof, although certain features thereof may be employed with equal advantage for other purposes.

It contemplates more especially the provision of an improved metallic shingle which has a novel inter-connecting means to preclude seepage or leakage of moisture therethrough for lodgment on a roof, and the accomplishment of this effectual joinder with minimum requirements for material from which the shingle is constructed.

Numerous types of metallic shingles have heretofore been proposed, but these have not proven entirely satisfactory because there is an undue requirement for excess material in forming flanges and other connecting expedients which do not prove especially efficacious in precluding leakage or moisture seepage therebetween. The requirement for the minimum utilization of material to cover a given area with effectual means to effect the joinder of adjacent shingles, constitutes an important problem which has not thus far been successfully solved without the provision of a shingle which is comparably expensive and less effectual. This is accomplished by the teachings of the instant invention by the provision of effectual joining expedients on shingles for complementary attachment with adjacent shingles on the roof surface to preclude any possible drain or seepage thereon even though the joinder thereof does not constitute a hermetically sealed connection.

One object of the present invention is to simplify the construction and improve the facilities for joining adjacent metallic shingles.

Another object is to provide a metallic shingle having integral flanges constituting improved connecting means precluding moisture seepage to the building structure.

Still another object is to provide metallic shingles having inter-connecting flanges which serve as a drain for any moisture to the exterior surface of the lower adjacent shingle.

A further object is to provide novel flanged connectors on metallic shingles without unduly increasing the material requirements therefor.

A still further object is to provide a novelly formed flange constituting a connector with complementary expedients provided on adjacent shingles as well as a drain for moisture that may seep therebetween.

Still a further object is to provide a shingle having a novel connecting flange which precludes or at least reduces moisture seepage to

a minimum and effects the drain thereof to the lower exterior surface of the lower adjacent shingle.

Other objects and advantages thereof will appear from the following description of an illustrative embodiment of the present invention.

In the drawing:

Figure 1 is a plan view of a shingle embodying features of the present invention.

Figure 2 is a view of a shingle substantially as viewed from line II—II of Figure 1.

Figure 3 is a sectional view taken substantially along line III—III of Figure 1.

Figure 4 is an end view of a shingle disclosed in Figure 1.

Figure 5 is a plan view of a modified shingle embodying features of the present invention.

Figure 6 is an end view of the shingle disclosed in Figure 5.

Figure 7 is a fragmentary view of a shingle viewed substantially from line VII—VII of Figure 6.

Figure 8 is a fragmentary view of a shingle viewed substantially from line VIII—VIII of Figure 6.

Figure 9 is a fragmentary view of a roof area showing the assembled relation of shingles of the type shown in Figure 1.

Figure 10 is a fragmentary view of a roof area showing the assembled relation of shingles of the type shown in Figure 5.

The structure selected for illustration comprises a substantially rectangular sheet 10 of material composed of aluminum or other materials which is of desired gauge or thickness to meet commercial requirements. The sheet 10 is provided with an elevated ridge 11 impressed therein along the side edge 12 which terminates in a reversely bent flange 13 disposed beneath the sheet 10 in alignment with the upstanding ridge 11 thereof. As shown, the reversely bent flange 13

serves to define the edge 12 and an edge 14 spaced therefrom so as to afford the telescopic reception of a complementary flange extending therebetween from an adjacent shingle. The reversely bent flange 13 has a bracket 15 depending from the edge 14 thereof for exposed extension upon the surface of the sheet 10. It is to be noted that the bracket 15 is connected to the flange 13 by virtue of an upstanding arm 16 which is of triangular configuration to sustain the flange 13 in an inclined direction for reasons which will appear more fully hereinafter.

The flange 13 is provided with apertures 17 to enable the attachment of the shingle 10 to the roof surface by resort to any suitable fasteners.

such as nails. The flange 13 extends from the top edge of the sheet 10 for a substantial distance downwardly just short of a lower edged flange 18 provided therealong. The inclination of the roof attaching bracket 15 imparts an inclination to the reversely bent flange 13 of a degree depending largely upon the slope of the roof surface and this is utilized for the purpose of draining any moisture seepage that may find its way within the flange 13 between the edges 12 and 14 thereof. To this end, the lower surface 19 of the flange 13 is depressed to define a runway 20 which guides the moisture along the edge of the sheet 10 for deposit on the exterior surface of the lower adjacent shingle 10.

It is to be noted that the other edge 21 disposed parallel to the edge 12 is provided with an opposite reversely bent flange 22 disposed beneath the sheet 10 for telescopic engagement with the reversely bent flange 13. The flange 22 has a portion 23 thereof spaced from the sheet connecting portion 24 for a distance sufficient to receive the edge 12 together with its upraised portion 11. In fact, the flanged portion 23 is spaced for a somewhat lesser distance so as to yield slightly responsive to its application over the edge 12 of the adjacent shingle to effect a hermetic joinder therebetween. With this arrangement, moisture seepage will practically be avoided or at least reduced to a minimum by virtue of the upraised edge portion 11 which precludes moisture flow or entrance therearound. Should the connection be somewhat distorted or imperfect for any reason whatsoever, then the moisture will be collected in the runway 20 and thence drain to the exterior surface of the lower adjacent shingle as will presently appear.

As described supra, the lower edge of the shingle sheet 10 is provided with a flange 18 turned therebeneath for engagement with an oppositely hooked flange 25 constituting the top edge of the sheet 10. In consequence, the adjacent shingles 10 are provided with supplemental flanges on all edges thereof for engagement and an edge shingle 10 is anchored or fastened to the roof surface by virtue of the bracket 15. Any suitable impressions such as an upraised shoulder area 26 may be provided in the shingle sheet 10 so as to impart a suitable design ornamental appearance to the shingle surface when assembled in a manner more clearly described in Figure 9. The adjacent shingles 10 are first anchored by means of a bracket 15, and thence they are overlapped along their sides for engagement to preclude moisture seepage and afford the drain thereof should any occur by reason of imperfect joinder or variations occurring before, during or after the placement thereof. It will be observed that minimum material is utilized in the attaching brackets and flanges so that the cost thereof is reduced to a minimum and an effective joinder between adjacent shingles rendered possible without entailing any undue labor or time in the installation thereof.

In the modified embodiment disclosed in Figures 5 to 10 inclusive, the side edged flanges 13' and 22' as well as the roof attaching bracket 15' are utilized as in the previously described structure. In this instance, however, the bottom flange 18' is provided with a reversely bent flange 27 which terminates in roof attaching brackets 28 for application to a roof surface along both the side and bottom edge for additional insurance. The top edged flange 25' is telescopically disposed between the bottom edged flange 18' and reverse-

ly bent extension 27 for engagement with the shoulder formed therein by virtue of a raised area 30 impressed therein. Otherwise the structures are substantially identical save for the additional bottom bracket 28 which is interrupted by a cut out portion 31 therebetween or along a vertical median line for rendering the top flange 21' of the lower adjacent shingle accessible for telescopic engagement and disengagement. 5

It is thus apparent that the shingles 10 and/or 10' are protected on all sides by flanges that are complementary to adjacent edges of successively laid shingles. The arrangement of parts above described affords the laying of shingles 10 and/or 10' from the top ridge of a roof to the eaves thereof. In other words, the shingles 10 and/or 10' are attached in horizontal alignment and inter-engagement along the ridge of the roof. These are individually laid for independent attachment by driving nails through the inclined flange 15 in shingle 10 and through both flanges 15' and 23 in shingle 10'. Thereupon, the top flanges 25 and 25' of the next lower tier or row of shingles are inter-engaged with the lower edge flange 18 and 18' of the above tier just previously laid, thereby affording top-down application of the shingles 10 and/or 10'. This coupled with complete inter-engagement along all edges with a special drain feature for all seepage, provides a novel, effective and comparably less expensive shingle from a material and labor standpoint. 30

Various changes may be made in the embodiment of the invention herein specifically described without departing from or sacrificing any of the advantages of the invention as defined in the appended claims. 35

I claim:

1. In a shingle that affords attachment to an inclined roof from the top down, the combination with a substantially rectangular metallic sheet, of a roof attaching bracket disposed along one side of said sheet, a reversely bent flange connecting said bracket and sheet to define spaced edges along said sheet side, there being a downwardly impressed trough along the lower side of said reversely bent flange to convey moisture therealong onto the succeeding shingle, and an opposite reversely bent flange on the side parallel to the first named side for telescopic inter-engagement with the first named flange on an adjacent shingle. 50

2. In a shingle that affords attachment to an inclined roof from the top down, the combination with a substantially rectangular metallic sheet, of a roof attaching bracket disposed along one side of said sheet, a reversely bent flange connecting said bracket and sheet to define spaced edges along said sheet side, said flange underlying said sheet, there being a downwardly impressed trough along the lower side of said reversely bent flange to convey moisture therealong onto the succeeding shingle, said bracket being inclined from the plane of said sheet by virtue of said reversely bent flange, and an opposite reversely bent flange on the side parallel to the first named side for telescopic inter-engagement with the first named flange on an adjacent shingle, said last named flange underlying said sheet. 60

3. In a shingle that affords attachment to an inclined roof from the top down, the combination with a substantially rectangular metallic sheet, of a roof attaching bracket disposed along one side of said sheet, a reversely bent flange connecting said bracket and sheet to define spaced edges along said sheet side, said bracket being in- 70 75

- clined from the plane of said sheet by virtue of said reversely bent flange, an opposite reversely bent flange on the side parallel to the first named side for telescopic inter-engagement with the 5 first named flange on an adjacent shingle, there being a downwardly impressed trough along the lower side of said reversely bent flange to convey moisture therealong onto the succeeding shingle, and oppositely bent flanges on the other edges 10 of said sheet to serve as a complement to flanges on adjacent shingles.
4. In a shingle that affords attachment to an inclined roof from the top down, the combination with a substantially rectangular metallic sheet, 15 of a roof attaching bracket disposed along one side of said sheet, a reversely bent flange connecting said bracket and sheet to define spaced edges along said sheet side, said bracket being inclined from the plane of said sheet by virtue 20 of said reversely bent flange, an opposite reversely bent flange on the side parallel to the first named flange on an adjacent shingle, there being a downwardly impressed trough along the lower side of said reversely bent flange to convey 25 moisture therealong onto the succeeding shingle, oppositely bent flanges on the other edges of said sheet to serve as a complement to flanges on adjacent shingles, and a roof attaching bracket extending from the flange on the lower edge of 30 said sheet.
5. In a shingle that affords attachment to an inclined roof from the top down, the combination with a substantially rectangular metallic sheet, 35 of a roof attaching bracket disposed along one side of said sheet, a reversely bent flange connecting said bracket and sheet to define spaced edges along said sheet side, said sheet having an upraised edge for emergence in said reversely bent flange to obstruct moisture passage, there being a downwardly impressed trough along the lower side of said reversely bent flange to convey 40 moisture therealong onto the succeeding shingle, and an opposite reversely bent flange on the side parallel to the first named side for telescopic inter-engagement with the first named flange on an adjacent shingle. 35
6. In a shingle that affords attachment to an inclined roof from the top down, the combination with a substantially rectangular metallic sheet, 45 of a roof attaching bracket disposed along one side of said sheet, a reversely bent flange connecting said bracket and sheet to define spaced edges along said sheet side, said sheet having an upraised edge for emergence in said reversely bent flange to obstruct moisture passage, there being a downwardly impressed trough along the lower side of said reversely bent flange, said bracket being inclined from the plane of said shingle sheet for imparting a corresponding inclination to said runway to convey moisture therealong onto the succeeding shingle, an opposite 50 reversely bent flange on the side parallel to the first named side for telescopic inter-engagement with the first named flange on an adjacent shingle, and flanges on the top and bottom edges of said sheet for inter-engagement with each other 55 on adjacent shingle sheets.

CHARLES J. RATEIKE.
